UNITED STATES PATENT OFFICE.

LEWIS E. HAWK, OF CHICAGO, ILLINOIS, ASSIGNOR TO CHICAGO SAFETY APPLIANCE COMPANY, OF CHICAGO, ILLINOIS, A CORPORATION OF ILLINOIS.

SAFETY DEVICE FOR ELEVATORS.

1,106,379.

Specification of Letters Patent. Patented Aug. 11, 1914.

Application filed January 5, 1914. Serial No. 810,280.

To all whom it may concern:

Be it known that I, LEWIS E. HAWK, a citizen of the United States, and a resident of Chicago, in the county of Cook and State 5 of Illinois, have invented certain new and useful Improvements in Safety Devices for Elevators; and I do hereby declare that the following is a full, clear, and exact description thereof, reference being had to the accompanying drawings, and to the letters of reference marked thereon, which form a part of this specification.

This invention relates to an electrically controlled safety mechanism more particularly intended for use in connection with hydraulic elevator systems, to stop or prevent movement of the elevator when any of the doors or gates of the elevator shaft are opened or stand in open position.

20 This invention consists of the matters hereinafter described and more particularly pointed out in the appended claims.

In the drawings: Figure 1 is a diagrammatic view in side elevation of a part of a 25 hydraulic elevator system with my invention applied thereto. Fig. 2 is a view on a larger scale partly in section and partly in elevation of my invention as applied to the pilot valve mechanism of a hydraulic elevator system. Fig. 3 is a plan sectional view through parts illustrated in Fig. 2, the plane of the section being indicated by lines 30 3-3 of Fig. 2. Fig. 4 is a detail sectional view through a switch mechanism located adjacent the pilot valve mechanism, the plane of the section being indicated by lines 35 4-4 of Fig. 3. Fig. 5 is a view of a switch mechanism used in connection with my invention, said switch being located in the 40 elevator shaft adjacent to and operated by the opening and closing of the doors in the elevator shaft.

In hydraulic or fluid operated elevator systems, a pilot valve mechanism is used for 45 controlling the inlet and discharge of the fluid under pressure to and from the operating engine. The pilot valve mechanism is operated by a main or controlling rock shaft on which is fixed an oscillating lever. 50 Movement is imparted to this oscillating lever by means of a cable extending vertically through the elevator shaft in a plane

adjacent the car and adapted to be operated from within the car in a well-known manner.

Referring more particularly to that embodiment of my invention illustrated in the accompanying drawings, 10 indicates an elevator car located in an elevator shaft 11, having the usual door openings 12 therein at each floor with the usual sliding doors 13 and 14 for closing said openings. The movement of the car in the shaft is controlled by an operating lever 10^a in the car 10, which lever operates upon a cable 20 in a well-known manner. The ends 20^a, 20^b of the cable operate a controlling valve mechanism 15, termed a pilot valve, of a hydraulic elevator engine (not shown), said pilot valve being placed adjacent the said engine which is generally located in the basement 70 of the building in which the system is installed.

The pilot valve 15 controls the fluid under pressure to the inlet and discharge cylinders of a hydraulic elevator engine, the system 75 being such that when the fluid under pressure is admitted to the engine through the pilot valve the car ascends in the shaft; when the supply to the engine is cut off by means of the valve, the car stops; and when 80 the valve is in position to allow the pressure in the engine to escape the car descends. The said valve mechanism 15 is operated by a rock shaft 16 which has bearing in a fixed bracket arm 15^a and has attached to it, 85 so as to move with it, a pair of laterally spaced rock arms 15^b. The outer ends of said arms 15^b are connected by a cross bar 15^c to which is attached a link 15^d by means of which the movement of the lever is communicated to the valve devices to operate 90 them.

18 indicates a lever fixed on the rock shaft 16 and 19 indicates a lever loosely mounted on said rock shaft in a position closely adjacent to the first named lever.

The lever 19 has oppositely extending arms 19^a, 19^b to which arms are connected the ends 20^a, 20^b of the operating cable 20. Fixed to the end of the arm 19^a is a horizontally disposed solenoid 21, to one terminal of which is connected a main line wire 22, the other terminal being connected to a wire 23. The said solenoid 21 has a core

24 which extends, as shown, through an aperture in the lever 18 and which, when said solenoid is energized, is drawn into said solenoid against the action of a light coiled spring 25 located therein. When said solenoid is deenergized the spring 25 will force the core 24 outwardly toward the lever 18.

10 The lever 18 has oppositely extending arms 18^a, 18^b which project beyond the ends of the arms 19^a, 19^b of the lever 19. The arm 18^a is provided with an aperture 18^c which is in line with the central axis of the core 24 of the solenoid 21 when the two levers 18 and 19 are in parallel relation and 15 which is adapted to receive the end of the core 24 when the solenoid 21 is deenergized. It is apparent that when the solenoid is deenergized and the core 24 thereof is projected into the aperture 18^c of the arm 18 20 any rocking movement given to the lever 19 by means of the cable 20 will be imparted to the lever 18, which will in turn cause a rocking movement of the shaft 16 so as to control the valve mechanism 15.

25 From the outer ends of the arms 18^a, 18^b at equal distances from the shaft 16 are suspended counterbalancing weights 18^d and 18^e. Said weights are suspended, as shown, by means of chains 18^f and 18^g each of which 30 is provided with a turn buckle 18^h to allow of adjustment of the length of the same.

35 When the lever 18 is in a horizontal position, the said weights rest on suitable supports 15^x, 15^y provided therefor. The turn buckles 18^h permit the length of the chains to be adjusted so that the levers 18 and 19 may be brought to a proper neutral position. When the lever 18 is brought to such angular position that the valve mechanism is operated to start the car up or down the shaft one of the weights will be in a position above its support while the other weight will be resting upon its support with its chain slack.

40 26 indicates a switch box located adjacent 45 the pilot valve 15. The said box is provided with a vertical slot 26^a in the side thereof toward the valve 15 and through the slot 26^a the arm 18^a of the lever 18 extends. The said box is preferably of rectangular 50 shape and of a height greater than its width and depth. Within said box are located vertically extending spaced arms 27, 27, one located on each side of the horizontal median line of the box. Each arm is pivotally 55 mounted on ears 28, 28 and suitably insulated from the box body. Also pivotally mounted on said ears 28, 28, and in the same plane as the arms 27, 27 are shorter arms 29, 29 which are held in contact with the upper 60 and lower edges of the end of the arm 18^a by means of leaf springs 30, 30 fixed at one end to the arms 27, 27 and bearing at their free ends against the shorter arms 29, 29. The ends of the arms 27, 27 are adapted to

engage against yielding contact pins 31, 31, 65 suitably mounted in the back wall of the box. Said pins 31, 31 are connected together by means of a wire 32 which is in turn connected to the wire 23 leading to one terminal of the solenoid 21. The arms 27, 27 70 when in their normal position contact against lugs 35, 35 formed in the casing 25. The said arms 27, 27 are suitably insulated from the lugs 35, 35 and are held in this normal position by means of coiled springs 75 36, 36.

To each arm 27, 27 are connected wires 37, 37 passing through suitable insulating bushings in the wall of the box 26. Each wire 37, 37 is connected to a line wire 38 (see Fig. 1), 80 the other end of which is connected to a fixed contact plate 39. Spaced a short distance from the contact plate and in the same plane is a second contact 40 which is connected to a main line wire 41. The space between the 85 contacts 39 and 40 is adapted to be bridged by the core 42 of a solenoid 43 in a manner to be presently described.

It is desirable to make the spaces between the ends of the arms 27, 27 and the spring 90 pressed contact pins 31, 31 as small as possible without danger of arcing between them. For this reason, the shorter arms 29, 29 are capable of yielding relative movement with respect to the arms 27 so that they may accommodate in their movement the relatively larger movement on the arm 18^a of the lever 18 required for it to fully throw the valve mechanism 15.

As before stated, the space between the 100 fixed contacts 39 and 40 is bridged by the movable core of a solenoid 43. To the terminals of said solenoid 43 are secured circuit wires 44, 45, preferably located in the elevator shaft.

105 46 indicates normally closed switches located in the elevator shaft, there being a switch adjacent each door opening 12 and each switch being adapted to be operated by the opening and closing of the associated door. The said switches each comprise a casing 50 in which is fixed a block of insulation 51, having spaced stationary contact members 52, 53. Each of said contacts 52, 53 are respectively connected to the main 110 circuit wires 44, 45 by means of wires 52^a, 53^a.

115 54 indicates a spring controlled, movable plunger suitably mounted in lugs 50^a, 50^b formed in said casing. On the plunger 54, 120 between the lugs 50^a and 50^b of the casing are formed shoulders 54^a, 54^b between which is fixed a block of insulation 55 to which is secured spring bridge contact arms 56. The 125 said shoulders 54^a, 54^b engage against the said lugs 50^a, 50^b respectively when the plunger is at one or the other limit of its movement. The spring contact arm 56 bridges

the contacts 52, 53 when the plunger is at one limit of its movement and closes the circuit. When the plunger is in its other position, the circuit is broken, as shown in Fig. 5.

5 To the plunger 54, adjacent the lugs 54^b, is fixed a shoulder 57, and surrounding said plunger between the shoulder 57 and the adjacent end wall of the box is a coiled spring 58. This coiled spring tends to move the 10 plunger with its spring arm 56 away from the contacts 52, 53. This pressure is normally resisted when the door is closed by an abutting shoulder or stop 60 carried by the door in line with and adapted for engagement 15 with a buffer head 61 formed on the end of the plunger 54.

From the above description, it is apparent that when the door is in closed position, the stop 60 abuts against the buffer head 61 of 20 the plunger and holds the spring arms 56 in position to bridge the space between the contacts 52 and 53 against the action of the spring 58. When the door is open, the spring 58 acting on the shoulder 57 will move the 25 plunger with its spring contact arm 56 away from the contacts 52, 53 so that the circuit is broken between the said contacts. Thus, when the door is in open position the circuit in the switch box is open so that the circuit 30 of the solenoid 43 is open and said solenoid deenergized. In such case, the core 42 acted upon by gravity, rests upon and bridges the contacts 39, 40 closing the circuit between the wires 38 and 41.

35 The operation is as follows: With the parts in position shown in Fig. 1, the car 10 is illustrated as stopping at the door 14 which is just being opened. The opening of the door has broken the circuit in the switch 40 box 50, said breakage deenergizing the solenoid 43 allowing core 42 to drop and bridge the contacts 39 and 40, thus connecting the wires 38 and 41. At this time, the levers 18 and 19 are still locked together, both levers 45 being in a horizontal position with the pivoted arms 29, 29 held in contact against the outer end of the arm 18^a by the leaf springs 30, 30. Should the operator of the car attempt at this stage to start his car by means 50 of the operating lever 10^a, the movement of said lever would be communicated through the cable 20 to the levers 19 and 18 and by the latter to one of the arms 29, the movement of which would immediately cause the 55 associated arm 27 to close on the associated contact pin 31. This would close the circuit of the solenoid 21 through the wire 32 and wire 23, cause the core thereof to be withdrawn and break locking connection between 60 the levers 18 and 19. This small initial movement of the levers has no effect on the controlling valve mechanism 15 and after the levers 18 and 19 have been disconnected as described, a further movement of the lever

19 by means of the cable 20 will be without 65 effect on the valve mechanism. Thus, it is apparent that any movement of the operating lever in the car while the door is in open position will not start the car. When the door 14 is again closed, said door will press 70 against the buffer 61 of the plunger 54 and move the same inwardly against the action of the spring 58 to bring the spring contact arms 56 into a position to bridge the contact members 52, 53 closing the circuit between 75 the wires 44, 45, thus energizing the solenoid 43. The core of said solenoid is raised and the circuit between the spaced contacts 39 and 40 is broken. This breaks the circuit of the solenoid 21 and the core 24 is moved out- 80

wardly by the action of the spring 25, said core entering into the opening 18^c in the arm 18^a to again lock the levers 18 and 19 together in the manner before described. A movement of the lever 10^a in the car 10 will 85 then act through the cables 20 and the levers 18 and 19 to rock the shaft 16 and operate the valve mechanism 15 as described.

When the car 10 is in motion in the elevator shaft 11 and the doors 13 and 14 thereof are in closed position, the operating lever 10^a will stand in an angular position. At this time, the levers 18 and 19 which are locked together by means of the solenoid core 24, have been rotated to rock the shaft 95 16 of the pilot valve 15 so as to allow the fluid to pass therethrough, the said levers 18 and 19 being in an angular position, one side or the other of the horizontal. This position of the levers 18 and 19 will carry one 100 of the weights 18^a and 18^e upwardly and away from its associated support 15^x, the other weight still resting on its associated support 15^x with its associated chain 18^f or 18^g in a slack position.

Should for any reason, one of the doors 13 and 14 be opened from any outside or inside agency, the circuit through the wires 44 and 45 would be broken as before described. This will cause the solenoid 43 to 110 be deenergized and the core 42 thereof will drop to bridge the space between the contacts 39 and 40 completing the circuit through the box 50 to the wire 23 to energize the coil 21 causing the core 24 thereof to be withdrawn from locking position between the levers 18 and 19, thus breaking the connection between the said levers. This would free the lever 18 from the influence of the 120 lever 19, and the weight 18^a or 18^e, whichever one has been moved upwardly away from its support 15^x, will fall by gravity and rotate the lever 18 which is fixed on the rock shaft 15 to its horizontal position shutting off the flow of fluid through said valve and stopping the car. This position is reached just when the weight which has been 125

moving downward by gravity strikes its associated rest 15^a. The position of the weight relative to the horizontal or cutting off position of the lever 18 may be regulated 5 to a nicety by means of adjustment of the turn buckles 18^b in the chain 18^c and 18^d. In order that the car may proceed, the lever 19 must be returned to neutral position and the open door closed, when all parts will 10 again be in position to start the car when the lever 19 is again moved.

It is apparent from the foregoing description that the elevator car can have no movement in the shaft as long as a door is open 15 even should the operating lever within the car be given movement, and should the operator attempt to leave the lever in a position to start the car with the door open, the connection between the levers 18 and 19 is 20 still broken, with the lever 18 in a neutral, horizontal position, having been returned to this position by the counterbalancing weights 18^d and 18^e and the lever 19 in an angular position corresponding to the angular 25 position of operating lever 10^a in the car 10. The lever 10^a must be brought to neutral position so that the arms 18 and 19 are in the same plane when they will again be locked together by the solenoid core 24. 30 This insures safety to the passengers entering and leaving the car as it is apparent that the operator cannot start his car until all the doors of the shaft are closed.

While I have described one form of mechanism for carrying out my invention, I do 35 not wish to be limited thereto except as pointed out in the appended claims.

I claim as my invention:

1. A safety device for hydraulic elevators, 40 comprising in combination with an elevator shaft having door openings therein, sliding doors adapted to close said door openings, and a car in said shaft, a controlling valve mechanism for controlling the movement of the car in said shaft, means operable from within the car for operating said controlling valve mechanism including a main operating member and an auxiliary operating member, means normally locking said auxiliary operating member to said main operating member, and means actuated by the opening of any of the doors in said elevator shaft for disconnecting the said auxiliary operating member from said main operating member.

2. A safety device for hydraulic elevators, 45 comprising in combination with an elevator shaft having door openings therein, sliding doors adapted to close said door openings, and a car in said shaft, a controlling valve mechanism for controlling the movement of the car in said shaft, means operable from within the car for operating said controlling valve mechanism including a main operat-

ing member and an auxiliary operating member, means normally locking said auxiliary operating member to said main operating member, means for automatically returning said main operating member to a neutral position when released from said auxiliary operating member, and means actuated by the opening of any of the doors in said elevator shaft for disconnecting the auxiliary operating member from said main operating member.

3. A safety device for hydraulic elevators, comprising in combination with an elevator shaft having door openings therein, sliding doors adapted to close said door openings, and a car in said shaft, a controlling valve mechanism for controlling the movement of the car in said shaft, means operable from within the car for operating said controlling valve mechanism including a rock-shaft, a main operating lever fixed on said shaft, an auxiliary operating lever loose on said shaft, means normally locking said auxiliary operating lever to said main operating lever, and means actuated by the opening of any of the doors in said elevator shaft for disconnecting the auxiliary operating lever from said main operating lever.

4. A safety device for hydraulic elevators, comprising in combination with an elevator shaft having door openings therein, sliding doors adapted to close said door openings, and a car in said shaft, a controlling valve mechanism for controlling the movement of the car in said shaft, means operable from within the car for operating said controlling valve mechanism including a rock-shaft, a main operating lever fixed on said shaft, an auxiliary operating lever loose on said shaft, means normally locking said auxiliary operating lever to said main operating lever, means acting to normally retain said main operating lever in neutral position, and means actuated by the opening of any of the doors in the elevator shaft for disconnecting the auxiliary operating lever from the main operating lever.

5. A safety device for hydraulic elevators comprising in combination with an elevator shaft and door openings therein, sliding doors adapted to close said door openings, a car in said shaft, a controlling valve mechanism for controlling the movement of said car in said shaft, a rock-shaft for operating said controlling valve mechanism, a cable operable from within the car for operating said rock-shaft, a main operating lever fixed on said shaft, an auxiliary operating lever adjacent the first named lever loose on said shaft, means for normally retaining said fixed operating lever in neutral position, electrically controlled means carried by said auxiliary operating lever for normally locking the same to said main operating lever

and electrically controlled means actuated by the opening of any of the doors in said elevator shaft for disconnecting the said auxiliary operating lever from said main operating lever.

5 In testimony, that I, claim the foregoing as my invention I affix my signature in the

presence of two witnesses, this 20th day of December A. D. 1913.
